UNITED STATES PATENT OFFICE.

JOHN GREEN, OF ST. LOUIS, MISSOURI.

PANEL-RAISING MACHINE.

SPECIFICATION forming part of Letters Patent No. 401,555, dated April 16, 1889.

Application filed October 10, 1887. Serial No. 251,963. (No model.)

To all whom it may concern:

Be it known that I, JOHN GREEN, of the city of St. Louis, in the State of Missouri, have invented a certain new and useful Improvement 5 in Panel-Raising Machines, of which the following is a full, clear, and exact description, reference being had to the accompanying drawings, forming part of this specification.

This is a wood-working machine intended especially for what is called "panel-raising," but applicable to other wood-working operations.

Figure I is an end view of the machine. Fig. II is a transverse section of the machine at II II, Fig. III. Fig. III is a side view of the machine, parts in section. Fig. IV is a perspective view of the table and parts above it. Fig. V is a detail perspective showing the 20 manner of supporting the table. Fig. VI is an enlarged detail perspective view at VI VI, Fig. XIV. Fig. VII is a top view of the cutter-head. Fig. VIII is a bottom view of the cutter-head. Fig. IX is a side view of the 25 cutter-head. Fig. X is a perspective view of a cutter. Fig. XI is a vertical section at XI XI, Fig. VII. Fig. XII is a perspective view of the table and parts above it, showing a modification of the cutters and a chip-breaking attachment. Fig. XIII is a side view of the parts shown in perspective in Fig. XII. Fig. XIV is a horizontal section at XIV XIV, Fig. XIII. Fig. XV is a section at XV XV, Fig. XVII. Fig. XVI is a side view of the 30 cutter-head, and Fig. XVII is a view of another side of the cutter-head. Fig. XVIII is a detail section at XVIII XVIII, Figs. XIII and XIV.

No novelty is claimed in the frame 1 or the 40 cutter-shaft 2 and its bearings. The cutter-shaft turns in an upper bearing, 3, and is stepped in a vertically-adjustable box or step, 4, supported on a hand-screw, 5, screwing in a fixed lug, 6.

7 is a belt-pulley on the cutter-shaft to receive the belt by which the shaft is turned.

The cutter-head has a horizontal disk, 8, secured to the shaft by a nut, as usual, and through or in which are made curved slots 9 45 for the engagement of the cutters 10. The

cutters are curved from end to end, and have at the upper edge an extension, 11, which fits in the slot 9, the point or outer end, 12, of the cutter extending beyond the slot and preferably past the periphery of the disk 8.

At one side of the slot are made notches or recesses 15, open at one side to the slot and beveled at the opposite side to give bearing to the side of a wedge-formed key, 16, one side of which bears against the cutter. The 55 keys 16 have screw-threaded ends 17, which extend above the top of the disk 8, where they receive nuts that bear upon the top of the disk, (or washers thereon,) and so hold the keys in place. The cutters have cutting-edges 60 13 at the bottom. The inner end, 14, of the cutter is at a distance from the center of the disk, and the cutter extends forwardly and outwardly in a curve from that point to the outer end, 12. The purpose of this is not 65 only to give the cutter a draw-cut on the stuff, but to all parts of the knife the same inclination to the direction of movement of the cutter. It will be seen that if the cutters were 70 straight and the edge deviating in any degree 75 from a direction radial to the head the inclination of the edge to the direction of movement would vary from end to end of the cutter, and that if the cutter were radial to the head the edge of the cutter would be at 80 right angles with the direction of movement, and consequently there would be no draw-cut. The cutting-edges 12 13 are shown meeting in a square corner; but the form of the cutter may be varied at this point, so as to change 85 the character of the work.

The table 18 is supported on the stand in such a way that it can be set at any desired angle transversely, so that the edge 13 of the cutter will cut the stuff to a bevel. The two 90 ends of the table are supported in the same manner, a description of the supporting device at one end applying equally to the other.

19 is a standard vertically adjustable in a recess in the end cross-bar, 20, of the main 95 frame. This standard is slotted vertically at 21 for the passage of a screw-bolt or screw-stud, 22, by which the standard is secured to the bar in any desired position as to altitude.

23 is a bracket fixed to the under side of the table and jointed to the top of the standard 19 at 24.

25 are links or supports at each side of the 5 standard, whose upper ends are jointed at 26 to brackets 27 and slotted longitudinally at 28 for the passage of screw-bolts or screw-studs 29, projecting from the bar 20, by which the links are held in any position. If the 10 nuts upon the screw bolts or studs 24 and 29 are made loose, the table may be bodily raised or lowered. If the nuts upon the studs 29 are alone made loose, the table may be tilted on the two standards 19. The table has a central aperture, 30, through which the cutter-shaft passes. Across this aperture extend bars 31, that support an adjustable bar, 32, upon which the inner end of the stuff rests. Each 15 end of the bar is held down to one of the 20 cross-bars 31 by a screw, 33, extending through one of the bars and screwing into the other bar.

34 is a screw at each end of the bars screwing in either the bar 32 or 31, and whose point 25 bears against the other bar. As shown, (see Fig. VI,) the screw 33 extends through a plain hole in the bar 31 and works in a screw-threaded hole in the bar 32, and the screw 34 works in a screw-threaded hole in the bar 32, 30 while its end bears upon the bar 31. By the vertical adjustment of the bar 32 or the cutter-head the thickness of the edge of the panel or other finished article is regulated.

The guide has two parts, 35, connected by 35 a bar, 36, said parts lying flat on the table and being attached thereto by screws 37 with thumb-nuts 38, said screws passing through transverse slots 39 in the guide. This means of attachment of the guide to the table enables the transverse adjustment of the guide. The guide has two guide-posts, 40, angular in transverse section.

41 is a guide-bar and chip-breaker located between the ends and at the outer edge of 45 the guide 35 35, which has upwardly-extending ends 42, which have bearings in the rabbit-grooves of the guide-posts.

43 are screw-studs extending from the bearing ends 42 through vertical slots 44 in the 50 posts 40. These screw-studs carry thumb-nuts 45, which bear against the posts and hold the guide and chip-breaker to its proper vertical position, the position being such that its outer side is in line with the face of the 55 guide and its upper side in close proximity to the lower edge, 13, of the cutters. The device acts as a chip-breaker by its contact with the edge of the stuff just beneath the level of the cut, thus giving support to the 60 edge and preventing any slivers being split off by the action of the cutters in cutting against the grain.

46 are standards on the guide, having transverse sockets carrying round bars 47, held in 65 position by set-screws 48. The bars are slotted for the reception of springs 49, that are held in position by set-screws 50. These

springs are curved upward at the ends, where they rest upon the stuff being operated upon to keep it down upon the bar 32.

In the modification shown in Figs. XII to XVII, inclusive, the chip-breaker and guide are shown as modified to suit a cutter-head having cutters suited to cut the edge of the stuff to a bevel. The chip-breaker 41 is beveled at the end, so that its edge may be set in close proximity to the edge 12 of the cutter, and it is connected to the upright flange 51 of the guide by a screw-bolt, 52, that passes through slots in the cutter and the guide-flange 51, said slots being marked, respectively, 53 and 54.

55 is an adjustable guide, which has both endwise and transverse movement. The guide 55 occupies a groove, 56, when in its inner position. It is attached by screws 57 to brackets 59, these screws passing through longitudinal slots 58 in the guide, which mode of attachment gives means for endwise or longitudinal movement of the guide 55. The 90 brackets 59 are attached to the main guide 35 by screws 60, which pass through slots 61 of the brackets. This mode of attachment gives means for the transverse adjustment of the guide 55.

To enable a better understanding of my invention I have fully shown and described in this application the cutter-heads used in connection with my apparatus; but I have not claimed the same herein, as such forms the subject-matter of the claims in my application, Serial No. 303,284, filed March 14, 1889.

I claim as my invention—

1. The combination, in a wood-working machine, of the transversely-adjustable guide 105 35, the vertically-adjustable guide and chip-breaker 41, and the adjustable bar 32, all constructed and connected substantially as set forth.

2. The combination, with the main frame 110 and table, of the brackets 27, secured to said table, the links or supports 28, hinged to said brackets, having slots, and bolts passing through said slots and securing said supports to the main frame, as set forth.

3. The combination, with the table and the cross-bars 20, of supports hinged to each corner of said table and having vertical slots therein, bolts passing through said slots and securing said supports to the cross-bars 20, recesses in said cross-bars, slotted standards set in said recesses and hinged to the table, and bolts passing through the slots in said standards and into said cross-bars 20, as set forth.

4. In a wood-working machine, the combination, with the table and the rotary cutter-head, of the combined guide-bar and chip-breaker 41, having the upwardly-projecting ends 42, adjustably secured to the table and adjustable to and from the cutter-head and adapted to serve as a side guide for the material, substantially as described.

5. The combination, with the guide-pieces 35 35 and the rotary cutter-head, of the com-

bined guide-bar and chip-breaker 41, arranged between the ends of and having slot-and-screw connection with said guide-pieces 35 35, whereby said guide-bar and chip-breaker 5 41 is adjustable to and from the cutter-head, substantially as set forth.

6. The combination, with the cutter-head and the guide-pieces 35 35, of posts secured to said guide-pieces, and the guide-bar and chip-breaker 41, having extensions 42, adjustably secured to said posts, substantially as set forth.

7. In a wood-working machine, the combination of the bar 32, adapted to support the 15 stuff, vertically-adjustable screws upon which said bar is mounted, springs adapted to bear upon the stuff above said bar, and supports for holding said springs, substantially as set forth.

20 8. In a wood-working machine, the combi-

nation, with the guide-pieces 35 35 and the bars 31, of standards carried by said pieces, a bar, 32, adjustably supported on said bars 31 and adapted to support the stuff, and springs adjustably secured to said standards 25 and adapted to rest upon the stuff, substantially as set forth.

9. The combination, with the cutter-head, the table, and the guide 35 35, having slot-and-screw connection with said table, of the 30 combined guide-bar and chip-breaker 41, having the vertical slot-and-screw connection with said guide 35 35, whereby said guide-bar and chip-breaker 41 is adjustable vertically and longitudinally to and from the cutter- 35 head, as set forth.

JOHN GREEN.
